LIGHT REFLECTING DEVICE

Filed Jan. 15, 1934

UNITED STATES PATENT OFFICE

2,054,014

LIGHT REFLECTING DEVICE

Chauncey E. Waltman, Chicago, Ill., assignor to
 Sandel Manufacturing Co., Chicago, Ill., a cor-
 poration of Illinois

Application January 15, 1934, Serial No. 706,595

1 Claim. (Cl. 240—81)

The invention relates to improvements in illuminating devices, and more particularly to an indirect lighting device.

The main object of this invention is to provide a device of this character adapted to reflect the rays of light from the burner upwardly against the ceiling and which has associated therewith means for diffusing downwardly and outwardly projected rays for the purpose of illuminating a shade which conceals the main reflector and source of light, whereby an ornamental effect may be produced upon the shade.

In an illuminating device of this character heretofore used, the reflector is surrounded by a shade, which shade conceals the reflector and source of light, and by reason of the reflector being of opaque construction the shade is not illuminated when the indirect light is in use. In order to produce local illumination and also to illuminate the shade, these devices generally provide side lights surrounding the main reflector. Thus when it is desired to produce the necessary illumination for the shade, it can be done only by the illumination of the side lights.

It is one of the objects of this invention to provide the main reflector which produces the indirect illumination with a glass light diffusing member adjacent the lower portion thereof, which member will be effective when the indirect light is in use to diffuse sufficient downwardly and outwardly projected rays for illuminating the shade. This it has been found can be accomplished without reducing to any material extent the indirect illuminating effect.

Another object of this invention is to provide in a device of the character described an opaque reflector which has associated therewith adjacent the lower portion thereof a glass light diffusing member for diffusing downwardly and outwardly projected rays for the purpose of illuminating the shade which conceals the reflector.

A still further object of this invention is to provide in a device of the character described an opaque reflector arranged around a source of light so as to substantially reflect the entire light rays emanating from said source upwardly against the ceiling; said opaque reflector having at its lower portion a glass light diffusing member surrounding the stem of the light bulb and which will be effective for diffusing the downwardly and outwardly projected rays of the light source for the purpose of illuminating the shade which is arranged around said main reflector for concealing the same.

A still further object of the invention is to

provide a device of the character described which will be simple in construction, assembly and operation and which may be produced along lines convenient for low cost manufacture and which will be highly efficient for carrying out the purposes for which it is designed.

With the foregoing and other objects in view, which will appear as the description proceeds, the invention consists in the several novel features of construction, arrangement and combination of parts, hereinafter more fully described, illustrated in the accompanying drawing, and particularly pointed out in the appended claim, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof from an inspection of which, when considered in connection with the following description, my invention, its mode of construction, assembly and operation, and many of its advantages should be readily understood and appreciated.

Referring to the drawing, the figure illustrated therein is a view partly in section and partly in elevation of an embodiment of my invention as arranged in a portable or stand lamp.

Referring to the drawing more specifically by characters of reference, the numeral 10 designates a pedestal or stand, preferably formed of hollow material or tubing, as is well known in the art, and is provided at its upper end with a holder or support 11 from which extend the side or external lamps. In the embodiment illustrated, I have shown my invention as being adapted to that type of lamp generally identified in the art as an indirect lighting lamp and which has associated therewith external lamps which may be of a construction adapted to simulate candle lamps. From the holder 11 extend hollow arms 12 which terminate at their free ends in suitable cup-shaped fixtures or brackets 13, within which brackets are adapted to be supported tubular bodies or sleeves 14 which may be constructed of a material such as fiber or the like, suitable for simulating candle sticks. Received within the upper ends of the sleeves 14 are incandescent lamps 15, which lamps will provide the local or direct illumination.

Supported above the holder 11 on the pedestal 10 is a hollow member 16, the upper end of which is internally threaded, as shown at 17, for a pur-

pose to be presently more fully described. Mounted within the hollow member 16 is an incandescent lamp securing bracket fixture 18 equipped with the usual pull chain switch (not shown), 5 the chain of which is received through an opening (not shown) formed in the member 16 whereby the switch may be actuated for energizing the electric incandescent lamp 19 disposed within the fixture 18, which lamp may be of the desired voltage.

In order to produce the indirect projection of light rays emitted from the lamp 19 with energization of its filament, I provide the bowl shaped reflector 20, which is made up, as shown in the drawing, with the side walls flaring outwardly and upwardly from a central opening 21, the inner surface only of said reflector possessing reflective properties, so that the greater or substantially all of the light from the lamp 19, arranged within the reflector 20, will be thrown upwardly against the ceiling. The lowermost edge of the reflector 20, surrounding the opening 21, is formed in the shape of an annular depending flange or collar 22 which is adapted to be spun around the upper edge of a barrel shaped glass diffuser 23, the bottom edge 24 of which is adapted to fit into and be supported by the cup shaped metal member 25, provided at its lower end with external threads for screw threaded engagement within the hollow member 16.

The glass light diffusing member 23 is arranged in relation to the lamp 19 and reflector 20 so as to provide for the diffusion of the rays of light that pass downwardly through the central opening 21 in the reflector 20 and also from that portion of the lamp 19 that extends below the bottom of the reflector 20. The reflector 20 and its associated diffusing member 23 are so disposed with respect to the lamp 19 that substantially all of the light rays emitted from the lamp will be projected upwardly by the reflector 20 and only a minor portion of said light will be permitted to pass downwardly through the opening 21 to be diffused by the member 23 for the purpose of illuminating a shade 26 of any suitable and well known construction, which shade is not only useful for shading the light 15, but is also effective for concealing the indirect reflector structure and the source of light, thereby giving the desired ornamental appearance to the device which is necessary in articles of this class.

In order to support the shade 26 upon the reflector 20, the upper portion of the shade is provided with a suitable wire frame 27 which is adapted to be loosely seated upon a shouldered flange 28 provided therefor upon the normal upper end of the reflector 20.

From the foregoing it will be readily understood by those skilled in the art that I have provided a lamp structure primarily adapted for producing indirect illumination which will provide for the desired illumination of the shade concealing the reflector and light source when only the indirect light is in operation.

65 The lack of illumination for the shade when the indirect lamp is in operation has been one of

the major defects in devices of this character. It will also be noted that this illumination for the shade is provided at practically no loss of indirect illumination. As already explained substantially all of the light rays emitted from the indirect lamp will be reflected by the reflector 20 and only a very small portion of said light rays are permitted to pass through the central opening 21 by reason of its constricted size for the purpose of being diffused by the diffuser 23. This small portion of the light rays, however, has been found to be sufficient for the purpose of providing the desired illumination of the shade.

Attention is also invited to the fact that the reflector 20, its associated diffuser 23 and supporting member 25 may be readily assembled and connected to each other by simple spinning operation resulting in a unitary construction which will be of a durable character and which may be assembled in a minimum of time and at a minimum cost for labor and materials.

It is believed that my invention, its mode of construction, assembly and operation, and many of its advantages should be readily understood from the foregoing without further description, and should also be manifest that while a preferred embodiment of the invention has been shown and described for illustrative purposes, the structural details are, nevertheless, capable of wide variation within the purview of my invention as defined in the appended claim.

What I claim and desire to secure by Letters Patent of the United States is:

A combined direct and indirect lighting fixture comprising a vertical standard, a lamp socket carried at the upper end of said standard, a socket cover surrounding said socket and having the upper portion thereof internally threaded, and a light reflecting and diffusing member supported in said socket cover by threaded engagement with the upper portion thereof, said last mentioned member comprising an opaque reflecting portion formed so as to project the light rays from a light source disposed within the socket in an upwardly and outwardly direction, said opaque reflecting portion being provided at its lower end with a central opening surrounded by a depending annular flange, and a barrel shaped glass-like diffusing member having its upper end secured within said depending flange of said reflecting portion and extending downwardly to surround the lower portion of the light source, the lower portion of said barrel shaped diffusing member being rigidly secured to an opaque support, the lowermost portion of which is in threaded engagement with the socket cover, the opening in said reflecting portion being of a relatively small size to permit only a small portion of the rays emitted from said light source to pass downwardly through said opening to be diffused by the light diffusing member, the lowermost portion of said light reflecting and diffusing member being arranged so as to close its bottom opening and prevent passage of light rays therethrough.
